UNITED STATES PATENT OFFICE.

JAMES A. LANSING, OF SCRANTON, PENNSYLVANIA.

COOKING-STOVE.

1,150,127.

Specification of Letters Patent. Patented Aug. 17, 1915.

Application filed April 23, 1915. Serial No. 23,401.

To all whom it may concern:

Be it known that I, JAMES A. LANSING, a citizen of the United States, residing at Scranton, in the county of Lackawanna and State of Pennsylvania, have invented certain new and useful Improvements in Cooking-Stoves; and I do hereby declare the following to be a full, clear, and exact description of the same, reference being had 10 to the accompanying drawings, forming a part of this specification, and to the figures and letters of reference marked thereon.

This invention relates to improvements in ranges and more particularly to a device for 15 lifting the top plate section of a range above the plane of the top of the range to permit ready access to the interior.

Objects of the invention are to provide a simple and efficient pan lifting device 20 which can be installed at a very low cost, and when installed, will not interfere with the other parts of the range, such as to hinder stoking of the firebox, for instance; to construct the top plate section lifting 25 arrangement in such manner that, when the top plate section has been elevated above the plane of the top of the range, it may be maintained in such elevated position without additional support than the lifting 30 device itself, an exceedingly simple arrangement, permitting the range to be used as a broiler, thereby saving the cost of broiler attachments; and also to so construct the lifting 35 device that it can be operated by a standard tool which may be readily detached from the lifting device and applied to other uses. For instance, the lifting device may be operated by an ordinary grate bar shaker, which is an accessory of every coal range, 40 thereby saving the necessity of supplying other accessories, and reducing the cost of installation to a minimum.

Other objects of the invention will appear 45 from the following detailed description of a structural embodiment of the invention in a preferred form, and the novel features thereof will be particularly pointed out in the appended claims.

In the drawings:—Figure 1 is a perspective of one type of range provided with the present improvements, showing the top plate section in elevated position and with

a part of the range broken away to more clearly illustrate the parts of the pan lifting device. Fig. 2 is a top plan view of the 55 range shown in Fig. 1 with the top plate section removed. Fig. 3 is a fragmentary front elevation of the range shown in Fig. 1. Fig. 4 is a detailed view of the parts of the top plate section lifting device detached from a stove and showing the parts in disassembled relation.

The range illustrated in the accompanying drawing is of the domestic cooking variety and embodies generally a range body 65 A having a firebox a inclosed by front and rear side plates a', a² and end plates a³, a⁴, respectively, said plates being assembled in a preferred manner to form a rectangular range frame. Supported upon the range 70 body A is the usual pan frame B having a ledge b projecting on all sides beyond said range body. A top plate section C having removable lids c, of usual type, is adapted to be detachably supported within frame B 75 and for this purpose said frame B may be provided with an opening b' for the reception of the top plate section C. The side walls of said opening b' are provided with an inwardly projecting ledge b² forming a 80 seat for the top plate section C and located a sufficient distance below the upper surface of frame B to permit the upper surface of top plate section C to lie flush therewith when positioned in the frame. Top plate 85 section C is adapted to be raised from and lowered into frame B to uncover and cover the entire firebox a, and, for this purpose, is provided with spaced rear brackets c', c² fitting into similarly spaced seats b³, b⁴ 90 located in the rear side wall of top plate section receiving opening b' and so arranged that, when the rear brackets c', c² are fitted into said seats, the top plate section C will be capable of a pivotal lifting and lowering 95 movement along a longitudinal axis substantially coincident with the rear wall of the top plate section receiving opening b'. It will be understood that the above description is of the parts of a range well known 100 in the art and is solely for the purpose of conveying a clear understanding of the improved pan lifting device, in which reside the substantial features of the invention.

The frame B is provided with a side seat b^5 extending transversely of the range along a projecting ledge b of the frame and located above an adjacent end plate a^4 , for instance, 5 of the range body. This side seat b^5 is preferably of less depth than the top plate section receiving opening b' of the frame B and is sufficient width to extend beyond the outer vertical wall of adjacent end 10 plate a^4 . Within said seat b^5 is an elongated transversely extending slot b^6 through which projects the lifting arm of the lifting device. The top plate section C is provided with a side extension or plate c^3 having a 15 substantial flat under surface. Said side extension c^3 corresponds in outline with seat b^5 and is approximately the same depth to enable said extension to fit nicely within the seat and lie flush with the upper surface 20 of frame B, when the pan is in lowered position.

The pan lifting arm D is adapted to project through transverse slot b^6 into engagement with the flat under face of plate c^3 25 when lifting top plate section C. As shown, lifting arm D is preferably curved and is provided with a substantially flat lifting face d , engageable with the flat under face of plate c^3 and so inclined with respect to 30 the lifting arm that when the arm and top plate section are in elevated position, said face d lies in a plane substantially parallel with the plane of the top plate section. In this manner, the lifting arm provides a flat 35 supporting surface for the top plate section when in elevated position, which prevents slipping of the top plate section and probable breaking of the parts of the range. The lifting arm D is carried by a rotatable 40 support d' having a circular socket d^2 fitting over a circular lug d^3 which projects from the outer wall of end plate a^4 and forms a fixed axis on which support d' and lifting arm D oscillate. Projecting out- 45 wardly from the support d' and substantially at right angles from the surface of end plate a^4 is a squared or otherwise poly-sided shank d^4 engageable with a suitable detachable tool, such as a grate bar shaker, 50 for instance, when it is desired to lift or lower the top plate section. The retaining member for the support comprises a segmental journal d^6 and a plate d^7 positioned against a side stop d^8 and a bottom stop d^9 , 55 both projecting from the outer wall of end plate a^4 . Said plate d^7 will be securely fastened to plate a^4 at e and stops d^8, d^9 will prevent slipping. Segmental journal d^6 is provided with an upper abutment e' and a 60 lower abutment e^2 , which abutments coöperate with abutting surfaces e^3, e^4 carried by rotatable support d' and form stops for limiting the oscillatory movement of the support and in turn the lifting arm D. Co- 65 operating lower stops e^2, e^4 limit the lower-

ing movement of lifting arm D and prevent falling thereof; coöoperating upper stops e', e^3 will be so arranged that the lifting arm D will be brought to a full stop in its lifting movement, just after the rotatable support d' has passed center. In this manner, 70 the lifting arm D, itself forms a support for maintaining the top plate section C in elevated position. Such an arrangement is of great utility for it permits the range to 75 be used as a broiler without incurring the cost of installing expensive broiler attachments.

It will be noted that all the parts of the improved lifting device are mounted exteriorly of the firebox, so that not only is a much longer life imparted to the parts themselves, but also they do not in any manner interfere with the other parts of the range nor with stoking of the firebox. 80 The arrangement is so simple that by merely applying a tool F to the shank d^4 and oscillating support d' the lifting arm D will lift the top plate section C and support it securely in elevated position against slipping on supporting surface d . The top plate section may be lowered by reapplying the tool F and oscillating the rotatable support d' in the opposite direction, coöperating lower stops e^2, e^4 preventing the lifting 85 arm D from falling too far so as to render it inconvenient to disengage tool F and apply it to other uses.

What is claimed is:—

1. In a range, the combination of the 100 range body, a top plate section mounted thereon for pivotal movement, said top plate section having a substantially flat under surface, a lifting arm pivotally mounted on the stove body and engageable with the flat 105 under surface of the top plate section to elevate it above the plane of the stove body, a stop for limiting the lifting movement of said arm, and means for throwing said arm past center into engagement with said stop 110 to lift the top plate section into extreme elevated position and support said section in such position by the engagement of the lifting arm with its flat under surface.

2. In a range, the combination of the 115 range body, a top plate section mounted thereon for pivotal movement, said top plate section having a substantially flat under surface, a lifting arm pivotally mounted on the stove, and engageable with the flat under surface of the top plate section to elevate it above the plane of the stove body, a stop for limiting the lifting movement of said arm, means for throwing said arm past center into engagement with said stop to 120 lift the top plate section into extreme elevated position and support said section in such position by the engagement of the lifting arm with its flat under surface, and a stop for limiting the releasing movement of 125

the arm to prevent its falling during release of the top plate section.

3. In a range, the combination of the range body, a top plate section mounted thereon for pivotal movement, a lifting arm pivotally mounted on the stove body and engageable with the top plate section to lift

it above the plane of the stove body, and a shank extending from the pivotal point of said arm and projecting substantially at 10 right angles from the plane of the stove body, said shank being adapted for co-operation with a detachable arm actuating lever.
